OTHER PUBLICATIONS

Canadian Trademark Application No. 1368594, Filed Oct. 23, 2007,
Ogilvy Renault LLP/S.E.N.C.R.L., S.R.L.*Primary Examiner* — Carol P Rademaker(74) *Attorney, Agent, or Firm* — Banner & Witcoff, Ltd.(57) **CLAIM**

The ornamental design for a bottle, as shown and described.

DESCRIPTION

FIG. 1 is a top, front, left perspective view of a bottle showing our new design;

FIG. 2 is a bottom, front, left perspective view thereof;

FIG. 3 is a front elevational view thereof;

FIG. 4 is a right side elevational view thereof;

FIG. 5 is a rear elevational view thereof;

FIG. 6 is a left side elevational view thereof;

FIG. 7 is a top plan view thereof; and,

FIG. 8 is a bottom plan view thereof.

The dot-dash-dot-dash broken lines shown in the drawings represent unclaimed boundaries of the claimed design.

The dot-dot-dot-dot broken lines shown in the drawings are included for the purpose of illustrating environmental structure and form no part of the claimed design.
